DESIGN FOR A CABINET FOR SOUND REPRODUCING DEVICES

George Kende, New York, N. Y., assignor to Universal Camera Corporation, New York, N. Y., a corporation of New York

Application April 12, 1946, Serial No. 128,522

Term of patent 14 years

(Cl. D56—4)

To all whom it may concern:

Be it known that I, George Kende, a citizen of the United States and a resident of the city, county, and State of New York, have invented a new, original, and ornamental Design for a Cabinet for Sound Reproducing Devices, of which the following is a specification, reference being had to the accompanying drawings, forming part thereof, in which:

Fig. 1 is a perspective view of a cabinet embodying my design; and

Fig. 2 is a vertical section of the front of the same cabinet, taken on the line 2—2 of Fig. 1.

The rear and other side of the design, not

shown in the drawing, are identical with the side of the drawing as shown.

I claim:

The ornamental design for a cabinet for sound reproducing devices, as shown and described.

GEORGE KENDE.
